Primary Examiner — Deanna L Pratt(74) Attorney, Agent, or Firm — Banner & Witcoff, Ltd.(57) CLAIM

The ornamental design for a cabana, as shown and described.

DESCRIPTION

FIG. 1 is a top, front, left perspective view of a cabana showing my new design;

FIG. 2 is a front view thereof;

FIG. 3 is a rear view thereof;

FIG. 4 is a left view thereof;

FIG. 5 is a right view thereof; and,

FIG. 6 is a top view thereof.

The broken lines depicting the remainder of the cabana show features that form no part of the claimed design.

1 Claim, 6 Drawing Sheets(56)
